UNITED STATES PATENT OFFICE

149,341

DESIGN FOR A SWIMMING POOL

Erling A. Clemetsen, Long Grove, Ill.

Application March 11, 1946, Serial No. 127,350

Term of patent 14 years

(Cl. D4—4)

To all whom it may concern:

Be it known that I, Erling A. Clemetsen, a citizen of the United States, residing at Long Grove, Prairie View, Illinois, have invented a new, original, and ornamental Design for Swimming Pool, of which the following is a specification, reference being had to the accompanying drawing, forming part thereof.

Figure 1 shows a top plan view of a swimming pool showing my new design.

Figure 2 is a sectional view along line 2—2 of Figure 1.

Figure 3 is an enlarged sectional detail along line 3—3 of Figure 1 to show the outline of the tank rim.

I claim:

The ornamental design for a swimming pool, as shown.

ERLING A. CLEMETSEN.
